UNITED STATES PATENT OFFICE

JAMES BARKER, OF KALAMAZOO, MICHIGAN

TEMPORARY BINDER

Application filed May 28, 1930. Serial No. 456,358.

The main object of this invention is to provide an improved temporary binder which may be readily opened from either side; that is, with the sheets disposed on either cover to permit insertion or removal of the sheets, or the entire sheet body may be easily removed as a unit and inserted in the covers.

A further object is to provide post bars adapted for use as holders in manipulating the sheets or as transfer bars.

A still further object is to provide a structure having these advantages which is well adapted for embodiment in books or binders of large dimensions and very securely retains the sheets.

Objects relating to details and economies of my invention will appear from the description to follow. The invention is defined and pointed out in the claims.

20 A structure which is a preferred embodiment of my invention is illustrated in the accompanying drawings, in which:

Fig. 1 is a front perspective view of my improved temporary binder with one of the 25 covers open.

Fig. 2 is an inside plan view with the upper post bar freed.

Fig. 3 is a fragmentary section on a line corresponding to line 3-3 of Fig. 1.

30 Fig. 4 is a fragmentary section on a line corresponding to line 4-4 of Fig. 2.

Fig. 5 is a fragmentary section through the post bars and sheets on line 5-5 of Fig. 2.

35 Fig. 6 is an enlarged fragmentary view with the parts in position shown in Fig. 2.

Fig. 7 is an illustration of my invention as embodied in a telescoping post type of binder partially in section on line 7-7 of Fig. 8,

40 the adjusting means for the clamping bars not being illustrated.

Fig. 8 is a fragmentary section on line 8-8 of Fig. 7.

In the embodiment of my invention illustrated, the covers 1 are connected by the flexible hinges 2 to the curved back 3. The covers have inwardly projecting parts 4 at their inner ends to which the links 5 are secured by the pivots 6, the structure illustrated having a pair of these links. The sheets shown

conventionally at 7 have slots 8 in their rear ends to receive these links.

I provide a pair of post bars 9 preferably chambered as in the embodiment illustrated and slotted from their rear edges at 10 to receive the links 5. Each of these post bars is provided with posts 11, the posts of the bars being disposed out of alignment so that they are in overlapping relation within the sheet body as illustrated in Fig. 5. I desire to point out that sectional posts may be employed if desired.

The post bars are detachably secured to the links 5 by means of the locking slides 12 arranged within the post bars and having bayonet-shaped slots 13 therein, the enlarged portions 14 of these slots being adapted to register with the openings 10 in the post bars when adjusted to one position so that the post bars may be engaged with the links by a lateral movement of the post bars and are locked to the post bars by these slides. I contemplate other means for certain embodiments but have not illustrated the same as it is believed that this disclosure will enable those skilled in the art to embody or adapt my improvements as may be desired.

With this arrangement of parts, either of the post bars may be released so that the sheet body may be split at the desired point for insertion or removal of the sheets, or both bars may be released so that the entire sheet body may be removed from the binder as a unit.

It will be observed that the openings in the locking slide are such that the links may swing within them as illustrated in Fig. 4 when released from one of the post bars.

In Figs. 7 and 8 I illustrate my improvements as embodied in a telescoping post type of binder in which the clamping bars 15 carry coacting telescoping posts 16 and 17. The adjusting means for the clamping bars are not illustrated, an adjusting means for binders of this type being well known in the art. The post bars 9 are manipulated the same as in the embodiment shown in Figs. 1 and 2, these post bars, however, being provided with sectional posts 18.

I have illustrated my improvements in two

embodiments or adaptations which it is believed will enable those skilled in the art to embody the same in various other relations of which they are capable.

5 Having thus described my invention, what I claim as new and desire to secure by Letters Patent, is:

1. In a temporary binder, the combination with covers, of links pivotally connected to 10 said covers, chambered post bars slotted from their rear edges to receive said links and provided with posts disposed out of alignment, and locking slides arranged within said post bars and having bayonet slots therein adapted

15 when the slides are in one position to register with said slots in said post bars permitting the engagement and disengagement of the post bars with the links and in another position to secure the post bars to the links.

20 2. In a temporary binder, the combination with covers, of links pivotally connected to said covers, chambered post bars slotted from their rear edges to receive said links, and locking slides arranged within said post bars 25 and having bayonet slots therein adapted when the slides are in one position to register with said slots in said post bars permitting the engagement and disengagement of the post bars with the links and in another 30 position to secure the post bars to the links.

3. In a temporary binder, the combination with covers, of links pivotally connected to said covers, post bars each provided with posts and slotted to receive said links permitting engagement and disengagement therewith by a lateral movement of the post bars, and locking slides on said post bars for detachably securing them to said links.

4. In a temporary binder, the combination 40 with covers, of links pivotally connected to said covers, post bars having transverse openings adapted to receive said links, and locking members on said post bars engageable with said links for detachably securing them to the links.

5. In a temporary binder, the combination with covers, of links pivotally connected to said covers, post bars each provided with posts and slotted to receive said links, and means on said post bars for detachably securing them to said links.

6. In a temporary binder, the combination with covers, of links pivotally connected to said covers, post bars having openings adapted to receive said links, and means on said post bars engageable with said links for detachably securing them to the links.

7. In a temporary binder, the combination with covers, of links pivotally connected to 60 said covers, and post bars each provided with posts and with independent means for detachably securing them to said links.

8. In a temporary binder, the combination with covers, binding elements extending between said covers, post bars each provided

with posts and slotted to receive said binding elements permitting engagement and disengagement therewith by a lateral movement of the post bars, and locking slides on said post bars for detachably securing them to said binding elements. 70

9. In a temporary binder, the combination with covers, of binding elements extending between said covers, post bars each provided with posts and slotted to receive said binding 75 elements, and means on said post bars for detachably securing them to said binding elements.

10. In a temporary binder, the combination with covers, of binding elements pivotally associated with said covers, post bars having openings adapted to receive said binding elements, and means on each of said post bars whereby they may be independently and detachably secured to said binding elements. 80 85

11. The combination in a temporary binder provided with binding elements, of post bars transversely slotted to receive said binding elements and provided with posts, and independent means for detachably securing said 90 post bars to said binding elements.

In witness whereof I have hereunto set my hand.

JAMES BARKER.
